UNITED STATES PATENT OFFICE.

EDWARD HUTCHENS, OF MILWAUKEE, WISCONSIN, ASSIGNOR TO UTILITY MANUFACTURING CO., OF CUDAHY, WISCONSIN, A CORPORATION OF WISCONSIN.

CRIMPING BEAD FLIPPER.

Application filed November 27, 1925. Serial No. 71,533.

This invention relates to bead flipping machines for wrapping fabric flipper strips around the beads used in pneumatic tires.

In my copending application, Serial No. 5 719,497, filed June 12, 1924, Patent No. 1,591,130, July 6, 1926, I have described a bead flipping machine in some respects similar to the present invention which is a development thereof especially adapted to 10 handle the more elastic grades of fabric which tended to spring back after stretching. It is therefore an object of this invention to provide means for crowding or shortening the center portion of the flipper strip 15 that contacts the bead, and to lay this fabric onto the bead, smoothing out the shortened center after positioning it on the bead. It has been found that by varying the amount of this shortening or crimping of the center 20 of the fabric strip that the conical angle of the outstanding flipper edges or skirt can be regulated or even turned backward, so great is the range of adjustment possible.

Other and further important objects of 25 this invention will be apparent from the disclosures in the specification and the accompanying drawings.

This invention (in a preferred form) is 30 illustrated in the drawings and hereinafter more fully described.

On the drawings:

Figure 1 is a front elevation of a complete machine embodying the feature of the invention with a completed bead in position 35 therein.

Figure 2 is an enlarged fragmentary view similar to Figure 1 showing the machine opened up for the insertion of a bead.

Figure 3 is a detailed plan view of the 40 flipper strip crimping mechanism.

Figure 4 is a section on the line IV—IV of Fig. 1 showing the driving mechanism.

Figure 5 is a detail view showing the 45 operation of the first stitching wheel.

Figure 6 is a detail view showing the operation of the second stitching wheel.

Figure 7 is a detail view showing the 50 operation of the third stitching wheel.

Fig. 8 is a detail view showing the operation of the folding rollers.

As shown on the drawings:

The embodiment chosen for illustration relates to the application of a rubberized flipper strip 10 to a bead ring 11, the edges 55 12 of the strip being lapped to form an out-

standing conical ring or skirt 13 which is built into the carcass of a pneumatic tire to retain the bead ring in position against the bursting pressure of the inflating air. It is therefore necessary to so form the outstanding skirt 13 as to lie in the proper direction to fit smoothly within the side walls of the tire carcass at a predetermined angle.

The machine itself comprises a base 14 and column 15 upon which is mounted a 60 bracket 16 supporting the driving motor 17 which actuates a train of gears through a clutch 18 which is under manual control by means of the bell crank 19, rod 20 and foot-lever 21. The train of gears comprises a 65 worm 22 and worm gear 23 with a pinion 24 engaging a gear 25 which is keyed to a shaft 26 carrying the main or bull wheel 27 as shown in Figure 4.

The top of the column 15 supports a 70 standard or backbone 28 which is apertured to form journals for all the driven elements operating within the bead ring. The various elements engaging the outer periphery of the bead ring are mounted on an arm 29 75 pivoted to the backbone at 30 and having a lever 31 conveniently located with regard to the operator's position to enable him to bring the elements on the arm into and out of contact with the work by means of the 80 connecting link 32. To maintain an orderly presentation of the subject, the various elements will be taken up in the order in which they apply to the work.

The bead ring proper is guided and held 90 from premature contact with the flipper strip by means of a hook 33. The fabric is led up under the bead ring over an adjustable guiding plate 34 which also serves to govern the stagger or overlap of the flipper edges. From the plate the fabric passes 95 over a driven crimping gear like roller 35, an adjustable idling crimper 36 bearing down thereon alongside the bead ring. The idler 36 can lead or follow the driven crimping rolls, thus materially affecting the crimp given the fabric and the depth it meshes into the crimping rollers is also adjustable, the arm 37 carrying the idler being pivoted 100 on the roller shaft 38 and clamped by the nut 39 in a slot. From the crimper the fabric and bead advance between the rollers 40 and 41, the two rolls serving to fold the fabric up both sides of the bead. A plate 42 is pivoted on the shaft 43 driving the roll 105 110

40 and carries the crimping and guiding mechanism heretofore described, the plate being clamped in position by the bolt 44 and serving to adjust the machine to the varying sizes and shapes of bead fillers to be covered.

After leaving the folding rollers, the two edges of the fabric are sensibly parallel as shown in Figure 5 and a series of stitching 10 rollers 45, 46 and 47 serve to progressively stitch and smooth out the fabric over the bead, the last roller acting to carry one edge of the fabric towards the other edge, the bull wheel 27 and a spring urged idler 48 15 completing the contact between the edges of the fabric and smoothing out the skirt into the desired conical section. The differential motion due to the conical surfaces of the bull wheel and idler serve to rub out 20 any air pockets trapped between the fabric edges. The rollers 45, 46, 47 and 48 are all adjustably mounted on the pivoted arm 29 and it is intended to vary the angles of mounting of these rollers if necessary to 25 provide for beads of varying cross section, such as clincher and straight side beads.

The gear train provided for driving the various inner rolls is shown in dotted line in Figure 2 wherein an idler gear 49 engages between the bull wheel gear and the gear 50 on the folding roller shaft 43, another idler gear 51 being interposed between the gear 50 and the gear (not shown) on the crimper shaft 38.

35 The sequence of operations have been described above in the presentation of the elements as they are brought to bear on the bead.

I am aware that many changes may be 40 made, and numerous details of construction may be varied through a wide range without departing from the principles of

this invention, and I therefore do not purpose limiting the patent granted hereon, otherwise than necessitated by the prior art.

I claim as my invention:

1. In a machine of the class described, means adapted to crimp the center of a flipper strip and means adapted to fold said strip about a bead filler.

2. In a machine of the class described, means adapted to crimp the center of a flipper strip, means adapted to fold said strip about a bead filler and means adapted to smooth out the skirt formed by the outstanding edges of said flipper strip.

3. In a machine of the class described, means adapted to crimp the center of a flipper strip, means adapted to fold said strip about a bead filler and means adapted to smooth out said crimped portion of the flipper strip after applying to the bead filler.

4. The method of applying flipper strips 65 to bead fillers comprising crimping the center portion of said strip and folding the strip about said bead filler.

5. The method of applying flipper strips to bead fillers comprising crimping the 70 center portion of said strip, folding the strip about said bead filler and stitching said strip to the bead to smooth out the crimped portion thereof.

6. The method of applying flipper strips 75 to bead fillers comprising crimping the strip material to produce an excess thereof, folding the same about said bead filler and stitching it about the bead to smooth out the crimped portion thereof.

In testimony whereof I have hereunto 80 subscribed my name.

EDWARD HUTCHENS.
